UNITED STATES PATENT OFFICE

2,418,222

OVERTRAVEL SWITCH ACTUATOR

Norman C. Fetter, Freeport, Ill., assignor, by
mesne assignments, to First Industrial Corpora-
tion, Wilmington, Del., a corporation of
Delaware

Application February 5, 1943, Serial No. 474,804

6 Claims. (Cl. 200—159)

1

This invention relates to switches of the pre-
cision snap-acting type and has special reference
to an improved actuator construction for operat-
ing the switch mechanism.

The principal objects of the invention are the
provision of a switch actuator of short length
mounted directly in the switch housing and ar-
ranged to abut directly against the switch con-
tact mechanism for operating the same, the
actuator comprising a tube having an end of
insulation material bearing against the switch
contact mechanism and the tube having support
for axial movement in a relatively long bearing
forming the mounting of the actuator and dis-
posed in the housing of the switch, the preferred
embodiment comprising telescoping tubes in
which an overtravel spring is enclosed within the
tubes and bearing against the insulated end so
as to insulate the actuating mechanism from the
switch, both tubes having bearing support in
said bearing, and one of the tubes carrying an
adjusting means at its end for adjusting the
effective overall length of the actuator.

Other objects and advantages will be apparent
from the following description and the accom-
panying drawing, in which—

Figure 1 is a section taken longitudinally
through a switch mechanism embodying my in-
vention, and

Fig. 2 is a side elevation with a portion of the
two switch housings broken away and showing
the moved position of the switch contact mecha-
nism and the switch actuator.

The actuator forming the subject matter of
this invention is designed for use with small pre-
cision snap-acting switches in which the size of
the switch mechanism and housing is a matter of
paramount importance. These switches are in-
tended for use in confined space and under ad-
verse conditions where a relatively large amount
of current must be switched and yet the dimen-
sions of the switch must be maintained at a
minimum and the parts must be protected from
adverse surrounding conditions. These switches
are designed for operation under a very small
differential of movement and under light oper-
ating pressures, and also are subject to damage
if excessive forces are applied to the switch con-
tact mechanism. For these reasons the form of
the switch operating mechanism becomes a mat-
ter of paramount importance, and this invention
deals primarily with an improved form of such
operating mechanism. The invention is herein
shown as embodied in a switch mechanism of the
type shown and described in my copending appli-

cation Serial No. 476,833 filed February 23, 1943
now Patent No. 2,374,986, dated May 1, 1945,
having a base 5 of insulating material and a cover
6 therefor, the base carrying a stationary contact
7 adjacent one end and a supporting means 8
adjacent the other end for supporting a switch
contact mechanism, which in this instance com-
prises a spring contact member 9 having two
spaced tension members 11, attached at one end
10 to the support 8 as shown, and a central com-
pression member 12, the opposite end of the com-
pression member having pivotal support in an
anchor 15 which in turn is pivotally mounted on
a bracket 16 of the support 8. The compression
member is stamped integral with the tension
members from a single piece of spring strip. The
tension and compression members, at their con-
nected ends, carry an extension 13 upon which
the mobile contact 14 is mounted. A spring 17
acts against the bottom of the anchor member 15
normally urging it upward and thus bringing the
contacts together in the manner shown in Figure
1. When the anchor 15 is forced downward to
the position shown in Fig. 2, the contacts are
caused to be separated to open a circuit thereat.
The base 5 and cover 6 form an inner insulating
housing for the switch contact mechanism, and
this inner housing is normally enclosed in an
outer housing 18 which is commonly formed of
metal and has provision as shown at 19 for at-
tachment to conduit or other means for enclosing
electrical conductors.

The cover 6 has an opening 21 above the anchor
15 and disposed in this opening is a bearing mem-
ber 22 which forms a bearing and a tubular guide
for the parts of the switch actuator. This bear-
ing member has a bore provided with a lower
bearing surface 23 and an upper bearing surface
24 separated by a shoulder 25. The outer sur-
face of the bearing member has a shoulder 26
adapted to abut against the outer surface of the
inner casing and the lower end of the bearing
member is riveted or spun over against the inner
side of the inner housing as shown at 27 to retain
the bearing rigidly in position on the inner hous-
ing. The bearing is of substantially greater
length than the thickness of the inner housing so
as to extend through an opening 28 in the outer
housing and at the same time to give greater
length to the inner bearing surfaces. Positioned
in the lower end of the bearing portion and seated
against the bearing surface 23 is a tube 29 hav-
ing an inwardly disposed shoulder 31 adjacent its
upper end and near the shoulder 25 of the bear-
ing member, the shoulder 31 being adapted to

abut the shoulder 25 to limit the upward movement of the tube. Disposed within the tube 29 is a second tube 32 having an outwardly disposed shoulder portion 33 adapted to abut against the shoulder 31 for the purpose of limiting the relative extension of the two tubes, the shoulder portion 33 being of substantial width slideable along the inner wall of the tube 29 upon relative axial movement of the tubes in providing overtravel movement to the actuator and to guide the lower end of the tube 32 against the inner wall of the tube 29 and thereby maintain alignment of the tubes throughout the length of travel of tube 32. Disposed across the lower end of the tube 29 is a button 34 having a crown portion 35 and an annular flange 36. The outer periphery of the flange 36 abuts against the shoulder 37 adjacent the end of the tube 29, and the outer end of the tube is riveted or spun over the outer surface of the flange 36 as shown at 38 to firmly retain the button in place spanning the end of the tube. The crown portion 35 is adapted to seat against the upper surface of the anchor member 15 so as to provide a substantially point contact as between the anchor and the actuator.

The upper end of the tube 32 has a shoulder 39 and a central threaded bore 41, the bore 41 receiving in threaded engagement an adjusting screw 42 having a crowned head 43, a lock nut 44 being disposed on the screw for the purpose of fixing the screw in adjusted position on the tube. A compression spring 45 abuts at one end against the shoulder 39 and at the other end against the insulating button 43. The button 43 has an upwardly extending central portion 46 which serves to prevent dislocation of the spring as is well known in the art. The spring 45 and tube 32 are inserted in the outer tube 29 prior to the attachment of the button, and thereafter the end of tube 29 is spun over the annular flange 36 of the button so as to hold the tubes, the spring and the button in assembled relationship.

It will be seen that the actuator is located in the housing in such manner that the crown 35 of the insulating button rests against or directly adjacent the upper surface of the anchor 15 when the anchor is urged upward against a stop screw 47 of the switch mechanism, and the shoulder 25 of the bearing member is in close proximity to the shoulder 31 of the lower tube. Also motion can be transmitted from the upper to the lower tube through the spring 45. While the strength of this spring can be selected as desired, in this instance the spring is of such strength that the anchor is depressed before any substantial compressive movement of the spring 45 occurs. Thus, when downward force is applied to the upper end of the adjusting screw 42, the actuator moves as a unit to force the anchor 15 and associated parts from the position shown in Figure 1 to that shown in Fig. 2 in which the anchor comes into contact with the upper face of the base 5 as shown at 48 and the overtravel mechanism does not come into operation during this movement. It will therefore be seen that during this movement the operating characteristics of the switch are substantially those which would prevail if the switch actuator were a single rigid member. However, when the anchor reaches the position shown in Fig. 2, continued downward movement of the adjusted screw 42 causes the upper tube 32 to telescope into the lower tube 29 and simultaneously compress the spring 39 in the manner shown in Fig. 2 allowing a substantial amount of overtravel to occur which in the absence of the

overtravel mechanism would be sufficient to damage the switch mechanism.

It will further be noted that this construction completely insulates the switch actuator from the switch contact mechanism but yet permits the actuator to rest directly against the mechanism so as to occupy a minimum of space from top to bottom. In this way the overall height of the switch mechanism and actuator is maintained at a minimum and sufficient space is provided for the provision of the adjusting screw 42 for the purpose of making close adjustments as between the actuator and the device from which the switch is operated. This construction also provides substantially complete enclosure for the spring mechanism and permits manufacture and assembly of the actuator as a unit. Furthermore, the construction is such as to provide a relatively wide bearing for both tubes, which bearing is disposed both within the inner switch housing and above it in the area normally occupied by the outer housing 18. This reduces to a minimum any deviation in operation due to side thrust of the external operating member against the head of the adjusting pin 42.

I claim:

1. The combination in an electric switch construction having a housing and a switch contact mechanism therein of an overtravel switch actuator comprising in combination two tubes disposed in telescoping assembly, one of said tubes sliding within the other for extending and contracting the assembly, stops at one end of each of said tubes for limiting the extension of said assembly, a button of insulating material secured in the other end of the larger of said tubes and adapted to bear against said switch contact mechanism to operate the same, an internal shoulder at the other end of the smaller of said tubes, a coil compression spring in said tubes bearing against said internal shoulder and against said insulating button to maintain said assembly in extended position, and a bearing disposed in a wall of said housing for reciprocally supporting said assembly, said bearing having separate bearing surfaces to fit each of said tubes for sliding movement of the assembly to actuate said switch contact mechanism.

2. The combination in an electric switch construction having a housing and a switch contact mechanism disposed therein, of an overtravel actuator comprising in combination a tubular bearing disposed in a wall of said housing and fixed thereto, two tubes supported in said bearing for sliding axial reciprocating movement therein, one of said tubes having sliding engagement within the other for extending and contracting said tubes, stops at one end of each of said tubes for limiting the extension of said tubes, a button of electrical insulation secured in the other end of one of said tubes and adapted to bear against said switch contact mechanism to operate the same, an internal shoulder at the other end of the other of said tubes, a spring in said tubes bearing against said internal shoulder and said insulating button and loaded in compression to normally extend said tubes, and a threaded adjustable push rod threaded into the other end of said other tube and extending into the coil of said spring adapted to be screwed in and out of said other end for the purpose of changing the extent of its projection from said other tube.

3. The combination in an electric switch con-

struction having a switch contact mechanism and a housing for enclosing the same, of an overtravel actuator comprising in combination a bearing fixedly disposed in a wall of said housing, two tubes mounted in said bearing for sliding axial reciprocating movement as a unit, a stop in said bearing member for limiting the outward movement of said tubes, one of said tubes having sliding engagement within the other for extending and contracting said tubes, stops at one end of each of said tubes for limiting the extension of said tubes, a button of electrical insulation secured in the other end of one of said tubes and adapted to bear against said switch contact mechanism to operate the same, an internal shoulder at the other end of the other of said tubes, and a spring in said tubes bearing against said internal shoulder and said insulating button and loaded in compression to normally extend said tubes, said spring having a strength sufficient to transmit the force required to actuate said switch contact mechanism without substantial distortion and to permit compression of the spring thereafter to provide overtravel movement in said actuator.

4. The combination in an electric switch construction having a switch contact mechanism and an enclosing housing therefor, of an overtravel actuator comprising a telescoping plunger including an outer tube having an internal shoulder at one end providing a stop and an inner tubular part telescoping therein, the tubular part having an enlarged annular shoulder on the outer surface thereof adjacent one end adapted to abut against said stop to limit the degree of extension of said plunger and to bear in sliding engagement against the inner surface of said tube to maintain said tubes in axial alignment, a spring within said tube and said tubular part for extending said plunger, means carried on the end of said tube for supporting the thrust of said spring and for bearing against said switch contact mechanism to actuate the same in response to axial movement of said plunger, said means comprising an insulating button affixed in the end of the tube and spanning the bore thereof for electrically insulating said actuator from said switch mechanism and a threaded adjustable push rod threaded into the other end of said tubular part adapted to be screwed in and out of said part for the purpose of changing the extent of its projection to change the effective length of the overtravel mechanism.

5. The combination in an electric switch construction having a switch contact mechanism and a housing for enclosing the same, of an overtravel actuator comprising a bearing member mounted in a wall of said housing and extending therethrough, said bearing member having coaxial upper and lower bearing surfaces, the lower bearing surface being of greater dimensions to provide a transverse shoulder therebetween, two tubes comprising an outer and an inner tube disposed in telescoping assembly mounted in said bearing

member, said outer tube being disposed in sliding and guiding relationship with said lower bearing surface and engageable with said shoulder to limit the movement of the assembly outwardly and said inner tube being mounted in sliding and guiding relationship with said upper bearing surface, a bearing shoulder on the outer side of said inner tube at one end thereof slideable along the inner wall of said outer tube upon telescoping movement of said tubes to maintain said tubes in axial alignment, a button of insulating material secured in one end of said outer tube adapted to bear against said switch mechanism to operate the same, an internal shoulder at the other end of said inner tube, and a coiled compression spring in said tubes bearing against said internal shoulder and against said button to maintain said tubes in extended position.

6. The combination in an electric switch construction having a switch contact mechanism and a housing for enclosing the same, of an overtravel actuator comprising a bearing member mounted in a wall of said housing and extending therethrough, said bearing member having coaxial upper and lower bearing surfaces, the lower bearing surface being of greater dimensions to provide a transverse shoulder therebetween, two tubes comprising an outer and an inner tube disposed in telescoping assembly mounted in said bearing member, said outer tube being disposed in sliding and guiding relationship with said lower bearing surface and engageable with said shoulder to limit the movement of the assembly outwardly and said inner tube being mounted in sliding and guiding relationship with said upper bearing surface, an annular stop on the inner side of said outer tube at one end thereof, a bearing shoulder on the outer side of said inner tube at one end thereof for abutment against said stop to limit the extended position of said tubes, said bearing shoulder being slideable along the inner wall of said outer tube upon telescoping movement of said tubes to maintain the tubes in axial alignment, a button of insulating material secured in one end of said outer tube adapted to bear against said switch mechanism to operate the same, an internal shoulder at the other end of said inner tube, and a coiled compression spring in said tubes bearing against said internal shoulder and against said button to maintain said tubes in extended position.
